UNITED STATES PATENT OFFICE.

CLARENCE MARSHALL, OF CHICAGO, ILLINOIS.

HAT-FASTENER.

1,259,763.

Specification of Letters Patent. Patented Mar. 19, 1918.

Application filed April 23, 1917. Serial No. 163,982.

To all whom it may concern:

Be it known that I, CLARENCE MARSHALL, a citizen of the United States, residing at Chicago, in the county of Cook and State 5 of Illinois, have invented certain new and useful Improvements in Hat-Fasteners, of which the following is a specification.

This invention relates to hat fasteners and more particularly to that type of 10 fastener which is mounted inside of the crown, so as to be invisible and is movable into and out of engagement with the wearer's hair. One of the main objects of the invention is to provide a device of the character 15 stated of extremely simple construction and operation which may be quickly and easily applied to a hat. A further object is to provide a device which may be formed by stamping and bending from sheet metal, or 20 other suitable material. Another object is to provide a device which can be produced at very small cost. A still further object is to provide a device having securing elements which, when in operative position, fit snugly 25 beneath the hat rim so as to be practically invisible and in such position as to eliminate all danger of their becoming entangled in the wearer's hair. Further objects will appear from the detailed description.

30 In the drawings:—

Figure 1 is a perspective view of the device as applied, the hat being indicated in broken lines,

Fig. 2 is a section through a hat with the 35 device applied taken substantially on line 2—2 of Fig. 1, and

Fig. 3 is a detail perspective view of one of the securing members.

At each side of the crown 1 of the hat 2 40 is secured a thin supporting plate 3. This plate may be formed from sheet metal or other suitable material and is provided with a plurality of spaced apertures 4 by means of which the plate is secured to the crown 45 of the hat, on the inner face thereof and a short distance above the rim 5 by thread passed through the openings and the hat crown. Preferably, though not necessarily, these plates are secured between the crown 50 of the hat and the hat lining 6, as indicated in Fig. 2 of the drawings. These plates may be slightly arched to fit the contour of the hat crown, or may be made of flexible material which is readily secured snugly against

the inner face of the hat crown by the fastening thread or equivalent means.

Each plate 3 is provided, at its central portion, with an off-set integral strap 7 which is formed by cutting two parallel spaced slits in the plate and then punching 60 the strip between these two slits outward so as to provide the offset strap. This strap slidably receives a securing member 8 which is formed of relatively thin spring steel, or other suitable resilient material. This member 8 is arched to conform approximately to the configuration of the side of a person's head, and is enlarged at its upper end to provide an integral head 9. This member 8 is also turned upward and outward at its 65 lower end to provide the integral outwardly extending finger 10. This finger is slightly arched in the direction of its longitudinal axis so as to correspond with the curvature of the under face of the hat brim 5. 75

In applying my securing device to a hat, the two plates 3 are secured in the crown, in the manner previously described, at each side thereof with the strap 7 directed inwardly of the hat crown, a suitable opening 80 being left in the lining 6 to accommodate the securing member 8. After the hat is placed upon the wearer's head, the securing members 8 are forced upwardly, by gripping the fingers 10. These members travel 85 upwardly and inwardly beneath the wearer's hair thus firmly securing the hat in position. When the members 8 are in their operative positions, the fingers 10 are positioned closely adjacent the under face of the 90 hat brim 5, and fits snugly against the same. In this position, these fingers are practically invisible and fit so snugly against the hat brim as to eliminate all danger of the wearer's hair becoming entangled with these 95 members. The heads 9 formed at the inner ends of the securing members 8, serve to prevent accidental withdrawal of the securing members, and also eliminate all danger of these members pulling through the strap 100 7 as will be clearly seen from Fig. 1 of the drawings.

A device constructed in this manner may be quickly and easily applied to a hat, and all of the parts of this securing device may 105 be produced very cheaply from sheet metal or other suitable material by stamping and bending. In addition, the securing mem-

bers are so shaped that, when in operative position, they present a very neat appearance and are entirely free of all points or projections such as might become entangled in the wearer's hair.

What I claim is:

1. The combination with a hat having an arched brim, of supporting plates secured to the inner face of the crown of said hat at opposite sides thereof and above said brim, and securing members formed from sheet metal and of smooth contour throughout their full length slidably mounted through said plates, said securing members being curved to conform substantially to the configuration of the side of the wearer's head, and each of said members being provided at its lower end with an outwardly directed finger arched to correspond with the arch of said brim so as to fit snugly against the brim and conform with the contour thereof when said securing member is in raised position.
2. The combination with a hat having a

crown and a downwardly arched brim, of two supporting plates secured to the inner face of the crown at opposite sides thereof, each of said plates having an integral offset strap, and a securing member formed from a flat strip of material slidably mounted through said strap and arched longitudinally to conform substantially to the configuration of the side portion of a person's head, said securing member being of smooth contour throughout its full length and provided at its lower end with an integral outwardly directed finger arched longitudinally to correspond with the arch of said brim so as to fit snugly against the underface of the brim when said securing member is in raised position.

In testimony whereof I affix my signature in presence of two witnesses.

CLARENCE MARSHALL.
